UNITED STATES PATENT OFFICE.

ERNEST ENGEL, OF LA MOURE, AND EMMA ROBERTS, OF EDMUNDS, NORTH DAKOTA.

JOURNAL-LUBRICATOR.

1,248,295.

Specification of Letters Patent. Patented Nov. 27, 1917.

Application filed October 26, 1916. Serial No. 127,925.

To all whom it may concern:

Be it known that we, ERNEST ENGEL and EMMA ROBERTS, citizens of the United States, residing at La Moure and Edinunds, respectively, in the counties of La Moure and Stutsman and State of North Dakota, have invented certain new and useful Improvements in Journal-Lubricators, of which the following is a specification.

- 10 This invention relates to an improved journal lubricator for cars and has as its primary object to provide an arrangement wherein the journal will continually run in oil without the use of the commonly employed waste as a packing for the journal and wherein a fresh supply of oil will be continuously furnished to the journal to effectually overcome any possibility of the heating thereof.
- 15 The invention has as a further object and more specifically to provide a device of this character employing a lubricant or oil receiving pan to be held to the journal so that the journal will run through the lubricant within the said pan and wherein an endless carrier will be provided for continuously pumping or transmitting a fresh supply of oil to the pan as the journal rotates.

20 And the invention has as a still further object to provide an arrangement wherein any slack in the carrier may be adjustably taken up and to also provide an arrangement wherein the said carrier will be yieldably tensioned to travel with the journal as the journal is rotated.

25 Other and incidental objects will appear as the description proceeds and in the drawings wherein we have illustrated the preferred embodiment of the invention and 40 wherein similar reference characters designate corresponding parts throughout the several views.

30 Figure 1 is a sectional view showing a conventional type of journal and box with 45 our improved lubricator operatively associated with the journal and shown in elevation within the box,

35 Fig. 2 is a sectional view more particularly showing the mounting of the lubricant receiving pan beneath the journal and the endless lubricant carrier or pump mounted to rotate with the journal,

40 Fig. 3 is an end elevation with the box

shown in section and particularly illustrating the mounting of the guard above the 55 lubricant carrier as well as the mounting of the rollers for adjustably taking up the slack in the carrier, and

Fig. 4 is a plan view showing the pan detached with the carrier guard illustrated 60 in section, this view particularly showing the troughs leading from the terminals of the guard into the pan for directing lubricant from the guard to the pan.

55 In order that the construction and operation of our improved lubricator may be accurately understood, we have illustrated in the drawings, a conventional type of journal box or casing 10 provided with a door 11 and operatively receiving the journal 12 of 70 a car axle 13. As is usual, the journal 12 is provided, at its outer extremity with an annular radial flange or shoulder 14 and fitted over the journal is a cap bearing 15.

65 Coming now more particularly to the subject of the present invention, a lubricant pan is employed having side walls 16, a bottom wall 17 which preferably slopes downwardly from opposite ends of the pan to deepen the pan, and an end wall 18 with 80 the opposite end of the pan closed by a bearing block 19 mounted between the said side walls. Arranged within the pan adjacent the extremity thereof opposite the block 19, is a similar block 20, these blocks 85 19 and 20 being cut away to fit against the journal 12 while the end wall 18 which is outwardly spaced from the shoulder 14 of the journal is similarly cut away to receive a corrugated pulley or sprocket 21 seating 90 against and connected to the adjacent end of the journal 12 by spaced bolts or other suitable fastening devices 22. At its outer end, the pulley 21 is formed with a radial flange 23.

95 Arranged beneath the pan adjacent opposite sides thereof are pairs of longitudinally extending reversely directed bowed springs 24 with the springs of each pair connected, at a point substantially midway 100 the ends thereof, as particularly shown in Figs. 1 and 2, by a rivet or other suitable fastening device. The lowermost springs of the said pairs are arranged to seat at their extremities against the bottom wall of 105 the casing or box 10 while the uppermost

springs freely engage at their extremities with the bottom wall 17 of the pan adjacent the ends thereof for yieldably supporting the pan beneath the journal 12 and holding 5 the bearing blocks 19 and 20 of the pan against the said journal with the journal extending within the pan.

Extending outwardly beyond the pulley 12 from the side walls 16 of the pan, are 10 oppositely disposed wings 25 preferably integral with the said side walls and projecting from the pan adjacent the upper margin thereof. Extending inwardly between the wings 25 are angle members 26 15 coöperating with the said wings to provide channel shaped shoulders or ledges with the upstanding walls of the said members each bent to form inwardly directed longitudinally extending flanges 27. The ledges 26 20 are arranged to slope downwardly from the outer extremities thereof in the direction of the pan and mounted upon the said ledges, is an arcuate lubricant guard or shield 28 extending over the pulley 21 in spaced relation thereto. This shield, at its extremities, 25 is formed with inwardly directed channel members 29 slidably fitting within the channels provided by the angle members or ledges 26 with the free upstanding walls of 30 the said channel members forming flanges 30 interfitting with the flanges 27 for detachably connecting the guard with the pan. The channel members 29 being received upon the inwardly and downwardly sloping ledges 26, are inclined in the direction 35 of the pan and the said channel members, at their inner extremities, are formed with reduced inwardly directed troughs or gutters 31 inclining downwardly and inwardly 40 to project at their inner extremities into the pan adjacent the side walls thereof. The gutters 31 are preferably integral with the channel members 29 and the body of the guard 25 and the inner side walls of the 45 said gutters, at the inner ends of the said channel members, are provided with openings or gates 32 for the channel members arranged over the pan at the adjacent extremity thereof.

50 It will now be observed that the outer extremities of the lowermost springs of the pairs of springs 24 are arranged to extend outwardly beneath the pulley 21 and connected to the adjacent terminals of the said 55 springs and extending transversely therebetween is a channel member 33. The side walls of this channel member are formed with longitudinally spaced openings for receiving pins 34 upon which are mounted 60 rollers 35. Trained around the said rollers to extend over the pulley 21 for engagement with the corrugated face thereof, is a sprocket chain or lubricant carrier 36 held 65 against displacement from the pulley by the flange 23.

As will now be clear, the carrier 36 will continuously travel about the pulley 21 and around the rollers 35 as the journal 12 is rotated, so that when the lower portion of the box or casing 10 is filled with oil, the 70 said carrier will continuously transmit or pump the oil from within the box up onto the said pulley to be deposited thereon when the said oil will run down around the pulley 75 to drop into the pan at the adjacent extremity thereof. The pan will, therefore, be at all times maintained full of oil and being yieldably held in operative relation with respect to the journal by the springs 24, 80 the said journal will constantly run in the oil within the pan to be maintained effectually lubricated. Furthermore, so long as the journal 12 is rotated, the carrier 36 will continuously act to replenish the oil as it is used or consumed from the 85 pan to at all times maintain the pan full. Any possibility of the heating of the journal is thus overcome.

The guard 28 is arranged to catch any oil flying from the carrier 36 as the said 90 carrier travels about the pulley 21. Oil upon the inner face of the said guard will tend to run down the guard into the channel members 29 thereof. These channel members being inwardly inclined will then direct such oil inwardly toward the gates 32 as well as into the gutters 31 to fall within the adjacent end of the pan to thus contribute in supplying the pan with oil.

As will be best observed upon reference to 100 Fig. 3 of the drawings, the pins 34 may be adjustably positioned within the openings in the side walls of the channel member 23 for adjustably spacing the rollers 35 laterally with respect to each other and consequently taking up any slack in the chain or carrier 36. These rollers are preferably 105 so arranged with respect to each other that the said carrier will normally pull upwardly thereon against the tension of the lowermost 110 of the springs 24. These lowermost springs will, therefore, also act to yieldably hold the carrier in engagement with the working face of the pulley 21 so that the said carrier will, at all times, move with the 115 pulley upon the rotation of the journal 12.

It will therefore be seen that we provide a particularly efficient construction for the purpose set forth and a lubricator which will dispense with the use of the commonly employed waste as a packing for the journal 120 while, at the same time, the device may be readily employed in connection with rolling stock as now in use.

Having thus described our invention, what 125 we claim and desire to secure by Letters Patent is:

1. A journal lubricator including a pan, an endless lubricant carrier, means mounted to rotate with the journal and actively en- 130

- gaging the carrier for operating the carrier upon the rotation of the journal with the said pan disposed to receive lubricant deposited upon the said means by the said carrier, and means for supporting the pan in active position with respect to the journal with the said last mentioned means engaging the carrier for tensioning the carrier about the said first mentioned means.
- 10 2. A journal lubricator including a pan, an endless lubricant carrier, means mounted to rotate with the journal and actively engaging the carrier for operating the carrier upon the rotation of the journal with the said pan disposed to receive lubricant deposited upon the said means by the said carrier, and yieldable means for supporting the pan in active position with respect to the journal with the said last mentioned means operatively engaging the carrier for yieldably tensioning the carrier about the said first mentioned means.
- 15 3. A journal lubricator including a pan, an endless lubricant carrier, means mounted to rotate with the journal and actively engaging the carrier for operating the carrier upon the rotation of the journal with the said pan disposed to receive lubricant deposited upon the said means by the said carrier, and spaced rollers operatively supported by the said last mentioned means and engaging the carrier with the said rollers adjustable with respect to each other for tensioning the carrier about the said first mentioned means.
- 20 4. A journal lubricator including a pan, an endless lubricant carrier, means mounted to rotate with the journal and actively engaging the carrier for operating the carrier upon the rotation of the journal with the said pan disposed to receive lubricant deposited upon the said means by the said carrier, and springs for holding the pan in active position with respect to the journal, a channel member mounted upon the said springs, and rollers carried by the said channel member and engaged with the said carrier with the said rollers adjustable with respect to each other for taking up slack in the carrier and with the said springs acting to tension the carrier about the said first mentioned means.
- 25 5. A journal lubricator including a pan, ledges carried by the pan, a guard supported by the said ledges and provided at its extremities with gutters emptying into the pan, a lubricant carrier, means mounted to rotate with the journal and actively engaging the carrier for operating the carrier upon the rotation of the journal with the said carrier disposed beneath the guard and with the guard adapted to direct lubricant collecting thereon from the carrier into the said gutters to flow into the pan, the pan being disposed to receive lubricant deposited

upon the said means by the carrier, and means for supporting the pan in active position with respect to the journal.

6. A journal lubricator including a pan, ledges carried thereby and formed to provide flanged channel members, a guard mounted upon said ledges and provided at its extremities with channel members received within the channel members of said ledges with corresponding walls of the channel members of the guard forming flanges interfitting with said first mentioned flanges to connect the guard with the pan and with the said channel members formed to empty into the pan, a lubricant carrier, means mounted to rotate with the journal and actively engaging the carrier for operating the carrier upon the rotation of the journal with the pan disposed to receive lubricant deposited upon the said means by the carrier and with the guard arranged above the carrier and adapted to direct lubricant collecting thereon from the carrier into the channel members thereof, and means for supporting the pan in active position with respect to the journal.

7. A journal lubricator including a pan, wings extending therefrom, angle members connected to said wings and providing ledges, a guard supported by said ledges and provided at its extremities with gutters emptying into the pan, means mounted to rotate with the journal, a lubricant carrier actively engaged with said means to be operated thereby upon the rotation of the journal with the guard arranged above the carrier and adapted to direct the lubricant collecting thereon from the carrier into the said gutters to flow into the pan and with the pan disposed to receive lubricant deposited upon the said means by the carrier, and means for supporting the pan in active position with respect to the journal.

8. A journal lubricator including a pan, a pulley connected to the journal to rotate therewith, a lubricant carrier trained over said pulley to be operated thereby, and tensioning means for holding the carrier in active engagement with the pulley with the said means supporting the pan in active position with respect to the journal with the pan disposed to receive lubricant deposited upon the pulley by the said carrier.

9. A journal lubricator including a pan, an endless lubricant carrier, means mounted to rotate with the journal and actively engaging the carrier for operating the carrier upon the rotation of the journal with the said pan disposed to receive lubricant deposited upon the said means by the carrier, means for supporting the pan in active position with respect to the journal, and an adjustable connection between the said last mentioned means and the carrier.

10. A journal lubricator including a pan,

an endless lubricant carrier, means mounted to rotate with the journal and actively engaging the carrier for operating the carrier upon the rotation of the journal with the said pan disposed to receive lubricant deposited upon the said means by the carrier, and a guard mounted to extend over the said

means and emptying into the pan for directing lubricant collecting thereon from the carrier into the pan.

10

In testimony whereof we affix our signatures.
